C. FLAGSTAD.
BOX COVER AND FASTENING FOR SAME.
APPLICATION FILED APR. 19, 1920.

1,371,883.

Patented Mar. 15, 1921.

INVENTOR:
Cornell Flagstad,
By his ATTORNEY: J.M. Carlsen

UNITED STATES PATENT OFFICE.

CORNELL FLAGSTAD, OF MINNEAPOLIS, MINNESOTA.

BOX-COVER AND FASTENING FOR SAME.

1,371,883.

Specification of Letters Patent. Patented Mar. 15, 1921.

Application filed April 19, 1920. Serial No. 375,156.

To all whom it may concern:

Be it known that I, CORNELL FLAGSTAD, a citizen of the United States, residing at Minneapolis, in the county of Hennepin and 5 State of Minnesota, have invented a new and useful Box-Cover and Fastening for Same, of which the following is a specification.

My invention relates to box covers and 10 fastening means for same. The main object is to provide shipping boxes and crates with an improved cover and means for holding such cover latched, and also sealed if so desired.

15 In the accompanying drawing:

Figure 1 is a top view of a box equipped with my improved cover and fastening. Fig. 2 is an enlarged section on the line 2—2 in Fig. 1. Fig. 3 is a modification of Fig. 1. 20 Fig. 4 is an enlarged section on the line 4—4 in Fig. 3. Fig. 5 is a detail top view of the lower part or member of the catching and locking device with the element 29 in Figs. 6 and 7 omitted. Fig. 6 is a section on the 25 line 6—6 in Fig. 5. Fig. 7 is a detail top view of Fig. 8. Fig. 8 is a right hand end view of the element 29 in Fig. 6.

Referring to the drawing by reference numerals, 9 designates a box or crate of which 30 only the top portion is shown. Two opposite sides, or ends of the box may be a little higher than the other two sides, so that the cover 10 passes down between the highest sides 11 and rests upon the two lower 35 sides 12, as indicated in Figs. 1 and 2, but this is no essential feature of the invention.

The cover is divided in the middle into two sections 13, 14, which are attached together by two hinges 15, and may also have 40 a third hinge 15^a, as in Fig. 3. Each section has its outer edge supported by a strip or ledge 16 secured in the box, and close by the top of said ledges the sides 11 are provided with apertures 17 or it may be sockets or 45 cavities like 17^a to the left in Fig. 4.

When the cover is put in place on the box, two flat fingers 18, fixed on each cover section, engage in the sockets 17. In order to so engage and likewise to disengage the fingers, the middle of the cover is raised as 50 shown in dotted lines in Figs. 2 and 4, or as much higher as may be necessary.

When the cover is put on and in plane position it is latched or locked down by any 55 suitable catch that will answer the purpose, but as such catches may be of several forms

I will simply indicate their nature by showing a cover securing device for which I have already secured Letters Patent. Said device is clearly shown in Figs. 5 to 8. It consists 60 of a metal plate 19 securable by rivets or like means 20 up under the cover section 14, or in Figs. 3 and 4 up under an undivided rigid board 14^a of the cover.

Slidably inserted in the angular ends 21 65 of the plate and in guides 22, is a slide 23 having at one end a finger catch 24, and at the other end hooks 25 to limit the action of a spring 26, which at all times tend to move the slide as from right to left in Figs. 5 and 70 6, and thus cause its solid portion 27 to move into a notch 28 of a bracket 29. Said bracket has also an aperture 30 adapted to receive a wire or metal strip 31, whose ends may be secured in a seal-lock 32. The bottom end 33 of the bracket extends horizontally and is secured by screws 34 to the under side of a board 35, having a slotted hole up through which the body of the bracket extends and engages with the slide 80 of the member secured to the cover.

In Figs. 1 and 2 the board 35 is loose and rests with its ends upon the ledges 16 and carries only the bracket 29, but evidently the cover cannot rise in the middle as long 85 as its slide 23 is engaged with the bracket in an unbendable board underneath the cover. In Figs. 3 and 4 the cleat 36 carries the bracket 29 and the jointless board 14^a carries the plate 19 and its slide 23. It will be observed that said board 14^a or rather 13^a—14^a 90 is not secured to the cleats 36—37, but only to the cleats 38—39, while the rest of the boards in the cover are secured at 40 to all of said cleats. In Figs. 1 and 2 the cover 95 boards are secured at 43 upon cleats 41 and 42. The hinge 15 in Fig. 2 is secured up under cleats 42 (beyond the board 35) and the prongs 18 are also secured to the under-sides of the cleats. This is true of both cleats, 100 36, 39, 41 and 42. 44 is an aperture in the cover for reaching the locking device to operate it.

With the structure thus described the cover is as firmly and reliably secured in 105 place as if screwed or nailed down, and yet it is attachable and detachable in a moment and without tools, except for opening the seal in the case where a seal is employed.

What I claim is:

1. The combination with a box or crate having some distance below its top sockets

in two opposite sides, of a cover having fixed at its under side projections adapted to enter into the sockets, said cover being divided near its middle into two sections 5 and having upwardly bendable hinges connecting the adjacent edges of the sections, thus making the cover bendable upward at the joint of the sections, means for supporting the cover in plane position and means for locking it in plane position on the box so it cannot bend upward at the joint.

10 2. The structure specified in claim 1, and means for sealing the locking device.

3. The structure specified in claim 1, said locking means composed of two interlocking parts, one part carried by the cover and accessible for operation through an aperture in the cover, the other composed of a catch and an unbendable flat bar fixed thereto and arranged underneath the cover.

15 20 4. The structure specified in claim 3, said unbendable flat bar being secured to the underside of the cover.

In testimony whereof I affix my signature.

CORNELL FLAGSTAD.
